Attorney

UNITED STATES PATENT OFFICE.

ADAM H. GRISWOLD, OF DENVER, COLORADO.

BILLIARD COUNTER.

1,416,015.

Specification of Letters Patent. Patented May 16, 1922.

Application filed July 20, 1921. Serial No. 486,100.

To all whom it may concern:

Be it known that I, ADAM H. GRISWOLD, a citizen of the United States of America, and a resident of Denver, in the county of Denver and State of Colorado, have invented certain new and useful Improvements in Billiard Counters; and I do hereby declare that the following is a full, clear, and exact description of the invention, such as will enable others skilled in the art to which it appertains to make and use the same.

This invention has reference to improvement in game accessories, having for an object to provide an improved point or score keeping button such as is used in recording the various points made in the game of billiards or pool which will be particularly advantageous for replacing broken buttons upon a rod, wire or other support without necessity of disturbing such support or the remaining buttons thereon.

It is also an object of the invention to provide a button of the character mentioned which when arranged upon a support in assembled condition, will be positively prevented from being displaced therefrom and also, will be allowed free movement along the support as may be desired.

Other objects will be in part obvious and in part pointed out hereinafter.

In order that the invention and its mode of operation may be readily understood by persons skilled in the art, I have in the accompanying illustrative drawing and in the detailed following description based thereon, set out one embodiment of the same.

In these drawings:

Figure 1 is a side elevation showing a plurality of the improved counters upon a support;

Figure 2 is a front elevation of one of the counters;

Figure 3 is a similar view of one section of one of the counters;

Figure 4 is an edge view of a counter section;

Figure 5 is a like view; and,

Figure 6 is a disassembled perspective of a counter.

Having more particular reference to the drawings, in connection with which like characters of reference will designate corresponding parts throughout the several views, my improved button or counter comprises a pair of complimentary longitudinally

divided sections 1 and 2 having oppositely disposed radial slots 3 and 4 formed therein, the opposite side walls of said slots being cut at a bevel as clearly indicated at 5. Formed integral with the inner or plane faces of the sections 1 and 2 are radially disposed bosses or ribs 6 and 7, these ribs, as will be noted, being arranged in alignment with the inner ends of the respective slots 3 and 4 of said sections 1 and 2 and being formed with under cut sides 8, corresponding to the beveling at 5 of the opposite side walls of the slots in the button sections.

In order that the outer side of each of the extensions or ribs 6 and 7 will conform with the continuity of surface of the outer faces of the button sections 1 and 2, the same, as will be noted upon reference to the Figure 1 are beveled as at 9, while the upper portions thereof are formed plane to correspond with the central portions 10 of the sections 1 and 2.

In using my improved button, the complementary sections 1 and 2 are first disengaged by sliding the same in opposite directions. At this time, one of the sections of the button is engaged with the wire *w* on which the same is to be supported, whereupon the opposite section is moved onto the wire, which enters the radial slot therein. With continued engagement of the remaining section with the first section, its radial slot will move over the extension on said first section, while the slot of said first section will be closed by the engagement of the rib of the opposite section therein. With the several sections 1 and 2 thus assembled, the same

may be joined by an adhesive substance which has been previously applied to the inner surfaces thereof, although, of course, it is to be understood that various forms of connecting these sections in their assembled relation may be employed, such as conditions or preference may dictate. Due to the fact that the radial slots 3 and 4 and the extensions or ribs 6 and 7 are under cut or beveled, it will be understood that the same when once engaged will serve to prevent relative lateral and rotary movement as between the sections. The connecting means employed as between the two sections, will prevent disassembling of the sections.

With the button so assembled upon the wire *w*, it of course will be understood that the same may be moved freely therealong from one position to another as may be desired.

Manifestly, the construction shown is capable of considerable modification and such modification as is within the scope of my claims, I consider within the spirit of my 5 invention.

I claim:

1. A device of the character described comprising a body composed of longitudinally divided complemental sections having 10 oppositely disposed radial slots formed therein, oppositely disposed radial ribs formed on the inner sides of said sections aligning with the inner end of the slots in their respective sections and adapted to be 15 slidably introduced into the radial slots of the opposite sections, the walls of said slots and the sides of said ribs being formed to permit of their sliding introduction but to prevent of relative lateral movement be-

tween said sections subsequently to such introduction. 20

2. A device of the character described comprising a body composed of longitudinally divided complemental sections having oppositely disposed radial slots formed 25 therein the side walls of which are beveled, oppositely disposed radial ribs formed on the inner sides of said sections aligning with the inner ends of the slots in their respective sections, said ribs having under cut side 30 walls and being adapted for snug reception in the radial slots of their respective opposite sections whereby to prevent of relative lateral or rotary movement as between said sections. 35

In witness whereof I have hereunto set my hand.

ADAM H. GRISWOLD.
